UNITED STATES PATENT OFFICE

JOHN M. TRAVIS, OF ST. LOUIS, MISSOURI

DESIGN FOR A BEVERAGE DISPENSING CONTAINER

Application filed November 3, 1932. Serial No. 45,719. Term of patent 14 years.

To all whom it may concern:

Be it known that I, JOHN M. TRAVIS, a citizen of the United States, residing at St. Louis, State of Missouri, have invented a new, original, and ornamental Design for a Beverage Dispensing Container, of which the following is a specification, reference being had to the accompanying drawing, forming a part thereof.

I claim:

The ornamental design for a beverage dispensing container, as shown.

JOHN M. TRAVIS.
